EVALD ANDERSON, OF ALHAMBRA, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL SEPARATION OF SUSPENDED PARTICLES FROM GASES.

Application filed September 17, 1925. Serial No. 57,011.

This invention relates to apparatus for separation of suspended particles from gases by electrical action and particularly to the form of such apparatus in which the gases containing the particles are passed between electrodes maintained at a high potential difference and so constructed as to produce an electrical discharge from certain of said electrodes, resulting in charging of the suspended particles and the deposition of charged particles on the electrodes and particularly on the electrodes opposing the discharge electrodes.

The main object of the present invention is to provide discharge electrodes of such construction as to improve the operation of the electrical precipitator, and particularly of such character as to maintain a highly uniform distribution of the electrical discharge throughout the body of the gas being treated so as to result in a more complete and efficient precipitation of the suspended matter, and also to prevent arcing or disruptive discharge between the electrodes.

In electrical precipitators there is a tendency for concentration of the electrical discharge at certain portions of the electrodes leading to certain disadvantageous results. By reason of such concentration of the electrical discharge in such portions of the electrodes there is liable to be a large portion of the gas being treated which is not subjected to the action of such electrical discharge and consequently such portions of the gas may pass through the electrical precipitator without being subjected effectively to the electrical precipitating action. In order to ensure contact of all portions of the gas with the electrical discharge it has generally been necessary to make the gas velocity extremely slow or to make the conduit or gas treating space between the electrodes sufficiently long to ensure that all of the gas will be subjected to electrical action at some time in its passage through such space. Furthermore, by reason of such concentration of electrical discharge there is liable to be breaking down of the dielectric resistance of the gas to such an extent as to cause arcing or disruptive discharge which seriously decreases the efficiency of the treater by limiting the potential difference which may be maintained between the electrodes,

and by otherwise interfering with the operation of the precipitator.

I have found that by covering the discharge electrodes, which generally comprise fine wires or rods of small diameter, with suitable semi-conducting material so as to interpose a considerable resistance to the passage of current, concentration of the electrical discharge at any one portion or at a relatively limited number of portions of the discharge electrodes may be prevented. This may be considered as being due to the fact that the relatively high resistance of the semi-conducting coating on the surface of the discharge electrode prevents the passage of an excessive amount of current at any one point and particularly acts to prevent the passage of such a large amount of current as would otherwise result upon breaking down of the dielectric resistance of the gas and thus cause arcing or disruptive discharge as above described. A discharge electrode of this character may be employed in connection with a collecting electrode of semi-conducting or high resistance material, for example, as described in my Patent No. 1,541,677, dated June 9, 1925, or in connection with collecting electrodes of metal. In the first case it will be seen that in addition to the air gap two layers of semi-conducting material are interposed between the high tension and low tension sides of the precipitator, one surrounding the discharge electrode and the other at the collecting electrode while in the second case only the semi-conducting layer surrounding the discharge electrode is interposed.

The accompanying drawings illustrate embodiments of my invention and referring thereto:

Fig. 1 is a vertical transverse section of one form of my invention.

Fig. 2 is a section on line 2—2 in Fig. 1.

Fig. 3 is a section on line 3—3 in Fig. 2.

Fig. 4 is a horizontal section of a discharge electrode on line 4—4 in Fig. 1.

Fig. 5 is a vertical section of a tubular or so-called pipe treater embodying my invention.

Fig. 6 is a section on line 6—6 in Fig. 5.

Referring to Figs. 1 to 3 the embodiment of my invention shown therein comprises a casting or conduit 1 having inlet 2 and outlet 3 for the gas to be treated and provided with

any desired number of vertical partition walls 4 subdividing the interior of said conduit into a plurality of passages. The walls of the flue 1 and the partition 4 constitute the collecting or so-called passive electrodes and may consist of any suitable semi-conducting or high resistance material presenting sufficient conductivity for carrying the precipitating current but presenting sufficiently high resistance to reduce the tendency to excessive concentration of the precipitating current at a point or points of said electrodes. For this purpose said electrode members 1 and 4 may consist of re-enforced concrete or similar material, consisting for example of concrete walls of Portland cement and suitable aggregate and having metal re-enforcing bars or rods 5 which are arranged in spaced parallelism, for example vertically, and are connected together and to ground by wires or conductors 6. Suitable means such as hopper 7 may be provided below the flue 1 for receiving the material precipitated upon the collecting electrodes and removed therefrom by the action of gravity or in any other suitable manner.

Within the flue spaces between the walls 1 and the partition means 4 are provided discharge electrodes 8 consisting for example of metal wires, rods, or other conductors 8' of relatively small cross-section and having continuous and substantially smooth-surfaced coatings or coverings 9 of suitable semi-conducting material at all portions thereof opposite the collecting electrodes. Said discharge electrodes may be suspended from a supporting frame 10 mounted on insulators 11 in the usual manner of electrical precipitators of this character. Said semi-conducting coatings may consist for example of Portland cement concrete, preferably made up with a suitable amount of fine sand but with little or no coarse aggregate, or other suitable cementitious material with or without asbestos or other fibrous material incorporated therein for the purpose of preventing cracking of said material. Other semi-conducting materials may also be used for this purpose, for example, enamels containing sufficient incorporated conducting material to render the same semi-conducting, said conducting material consisting for example of conducting metal oxides, finely divided metals, carbon, etc. The term semi-conducting as used herein is applied to the general class of materials whose electrical conductivity is intermediate between that of substances which are generally considered good conductors, such as metals, carbon, etc., and that of materials which are generally considered non-conductors, such as glass, porcelain, quartz, rubber, etc. For the purpose of my invention I prefer to form the semi-conducting coatings or covers 9 of materials having an electrical conductivity, at

temperatures not exceeding 200° C., between the order of 10^{-2} and 10^{-6} reciprocal ohms per centimeter cube. Materials having an electrical conductivity within this range are adapted to permit the flow of sufficient electrical current to effect electrical precipitation and at the same time to prevent excessive flow of current to any part of the precipitator. The wires or rods 8' may be of any suitable small diameter, for example $\frac{1}{16}$ inch to $\frac{1}{8}$ inch or larger and the thickness of the semi-conducting coatings 9 may be varied, according to the material used and the conductance desired, for example from a mere film in the case of enamels to a thickness of $\frac{1}{4}$ inch or more in the case of cementitious materials.

The term "substantially smooth-surfaced" as applied to the semi-conducting coatings is not to be understood as precluding any minor roughness or unevenness which is inherent in the material used in such coating. Such coating should, however, as shown for example in Figs. 1 and 4, be of substantially uniform thickness, with a surface as smooth as it is practicable to obtain with the material used. Any minor roughnesses or protuberances which may occur are to be considered as merely incidental and unavoidable and are not relied upon according to this invention for facilitating electrical discharge therefrom. This construction is therefore to be distinguished from certain types of previously used discharge electrodes which comprise a conducting member with projecting fragments of non-conducting material secured thereto, in which case the projecting points or edges of the non-conducting material were intentionally provided for the purpose of facilitating electrical discharge therefrom.

I prefer to arrange the discharge electrodes 8 in parallel relation to the re-enforcements 5 in the collecting electrodes and opposite the spaces between such re-enforcements so as to equalize the electrical field intensity throughout the surface of the collecting electrodes as set forth in my patent above referred to.

The operation of this form of the invention is as follows:

A high potential difference, preferably unidirectional, is applied to the electrodes for example by connecting the high tension system carrying the discharge electrodes 8 through wire 12 to any suitable source of high tension rectified alternating current for example in the manner set forth in U. S. Patent to F. G. Cottrell, No. 895,729, dated August 11, 1908. A strong electric field is thus produced between the surfaces of the semi-conducting coatings 9 of the discharge electrodes 8 and the surface of the opposing collecting electrodes 1 and 4 with the result that an electrical discharge takes place

mainly from the discharge electrodes on account of the relatively limited cross-section and correspondingly sharp curvature thereof. Such electrical discharge takes place 5 from the surface of the semi-conducting coating 9 of each discharge electrode and the current must therefore pass through said semi-conducting material, which prevents undue concentration of the electrical field 10 at any portion of such surface. This effect is further increased in this case by the semi-conducting character of the collecting electrodes 1 and 4, with the result that a very uniform distribution of electrical discharge, 15 corona, or ionization is maintained throughout the body of gas passing between the electrodes and a more rapid, complete, and uniform electrical charge of the suspended particles in the gas is secured with resulting 20 rapid and complete electrical precipitation of such suspended particles. Such precipitation takes place in the usual manner of electrical precipitation operations, by translation of the electrically charged particles 25 under the action of the electrical field toward the collecting electrode, it being understood that the particles will be electrically charged in the same sense as the discharge electrodes and will therefore be forced by 30 the action of the electrical field away from the discharge electrodes and towards the collecting electrodes. Due to the uniform distribution of the electrical field, and the prevention of arcing and disruptive dis- 35 charge brought about by the semi-conducting coating on the discharge electrodes and the semi-conducting nature of the collecting electrodes, a very high potential difference may be safely maintained between the 40 electrodes without danger of producing disruptive discharge.

The discharge electrode provided with a semi-conducting coating according to my invention may also be used in connection with 45 metallic or conducting collecting electrodes. As an example of this I have shown in Figs. 5 and 6 a precipitator of the tubular or pipe type comprising a vertical tubular casing 13 formed for example of steel, cast iron, or 50 other suitable metal and a discharge electrode 14 mounted so as to extend axially within the tubular casing 13 and consisting of a wire, small rod or other conductor 14' provided with coating or covering 15 of semi- 55 conducting material such as a semi-conducting enamel of the type above described. Said discharge electrode may be mounted on suitable insulating means 16 and may be provided at its lower end with tensioning means 60 such as weight 17. The discharge and collecting electrodes are in this case provided with electrical connections similar to those

shown in Figs. 1 to 3 and the operation of this form of my invention is substantially the same as that above described. It will of 65 course be understood that in practice any suitable number of vertical flues or pipes 13 may be connected in parallel arrangement in the usual manner of multiple pipe electrical precipitators, a discharge electrode 14 pro- 70 vided with a semi-conducting coating being arranged within each of said flues.

I claim:

1. In apparatus for electrical precipita- 75 tion of suspended particles from gases, a dis- charge electrode comprising a conducting member and a continuous coating of semi- conducting material surrounding said conduct- ing member.

2. In apparatus for electrical precipitation 80 of suspended particles from gases a dis- charge electrode comprising a conducting member, and a continuous coating of semi- conducting material surrounding said conduct- ing member, said semi-conducting mate- 85 rial having an electrical conductivity, at temperatures not exceeding 200° C., between the order of 10^{-2} and 10^{-6} reciprocal ohms per centimeter cube.

3. An apparatus for electrical precipita- 90 tion of suspended particles from gases com- prising a collecting electrode presenting a relatively extended surface and a discharge electrode opposing said collecting electrode and presenting a relatively small surface and 95 sharp curvature, said discharge electrode comprising a conducting member and a con- tinuous coating of semi-conducting material surrounding said conducting member, at all portions thereof opposite said collecting elec- 100 trode and means for maintaining a high po- tential difference between said discharge and collecting electrodes.

4. An apparatus as set forth in claim 3, 105 said collecting electrode being of semi-con- ducting material so as to present high resist- ance throughout its area.

5. In apparatus for electrical precipita- 110 tion of suspended particles from gases, a dis- charge electrode comprising a conducting member and a continuous coating of semi- conducting cementitious material surround- ing said conducting member.

6. In apparatus for electrical precipitation 115 of suspended particles from gases, a dis- charge electrode comprising a conducting member and a continuous and substantially smooth-surfaced coating of semi-conducting material surrounding said conducting mem- 120 ber.

In testimony whereof I have hereunto sub- scribed my name this 11th day of September, 1925.

EVALD ANDERSON.
